A. S. Dodd.
Design Carriage.
Patented AUG 30 1870# United States Patent Office.

AMZI S. DODD, OF NEW YORK, N. Y.

Design No. 4,306, dated August 30, 1870.

DESIGN FOR A CARRIAGE.

The Schedule referred to in these Letters Patent and making part of the same.

To all whom it may concern:

Be it known that I, AMZI S. DODD, of the city of New York, in the county and State of New York, have invented a new and original Design for Wheeled Vehicles; and I do hereby declare that the following is a full, clear, and exact description thereof, which will enable others skilled in the art to make and use the same, reference being had to the accompanying drawing forming part of this specification.

This invention relates to a new and improved design for either one or two-horse carriages, for transporting passengers in cities and towns, and consists in the peculiar form and style of the carriage, whereby the carriage is given a light, airy, and beautiful appearance.

In the accompanying drawing—

Figure 1 is a top view;
Figure 2 is a front view;
Figure 3 is a side elevation; and
Figure 4 is a rear elevation.

Similar letters of reference indicate corresponding parts.

The corners of the carriage are rounded, as seen in fig. 1, and the door at the rear, and the sides and front

of the carriage are filled with glass panels, as seen in figs. 2, 3, and 4.

A is the door.

B is the step.

C is the driver's seat.

D, the lamps.

E, the springs, upon which the body F is supported from the rear axle.

G is the foot-board.

H is the spring which supports the front of the carriage.

J represents the glass panels.

Any style of ornamentation above and below the glass panels may be adopted, and any name or designation may be given the vehicle.

I claim as my invention—

The design for a carriage, substantially as shown and described, for the purposes set forth.

The above specification of my invention signed by me this 11th day of March, 1870.

AMZI S. DODD.
